FIG. 1

FIG. 2

FIG. 3

FIG. 4

FIG. 5

**CUE-AWARE PRIVACY FILTER FOR
PARTICIPANTS IN PERSISTENT
COMMUNICATIONS**

TECHNICAL FIELD

The present disclosure relates to inter-device communication.

BACKGROUND

Modern communication devices are growing increasingly complex. Devices such as cell phones and laptop computers now often are equipped with cameras, microphones, and other sensors. Depending on the context of a communication (e.g. where the person using the device is located and to whom they are communicating, the date and time of day, among possible factors), it may not always be advantageous to communicate information collected by the device in its entirety, and/or unaltered.

SUMMARY

The following summary is intended to highlight and introduce some aspects of the disclosed embodiments, but not to limit the scope of the invention. Thereafter, a detailed description of illustrated embodiments is presented, which will permit one skilled in the relevant art to make and use aspects of the invention. One skilled in the relevant art can obtain a full appreciation of aspects of the invention from the subsequent detailed description, read together with the figures, and from the claims (which follow the detailed description).

A device communication is filtered according to an identified cue. The cue can include at least one of a facial expression, a hand gesture, or some other body movement. The cue can also include at least one of opening or closing a device, deforming a flexible surface of the device, altering an orientation of the device with respect to one or more objects of the environment, or sweeping a sensor of the device across the position of at least one object of the environment. Filtering may also take place according to identified aspects of a remote environment.

Filtering the device communication can include, when the device communication includes images/video, at least one of including a visual or audio effect in the device communication, such as blurring, de-saturating, color modification of, or snowing of one or more images communicated from the device. When the device communication includes audio, filtering the device communication comprises at least one of altering the tone of, altering the pitch of, altering the volume of, adding echo to, or adding reverb to audio information communicated from the device.

Filtering the device communication may include substituting image information of the device communication with predefined image information, such as substituting a background of a present location with a background of a different location. Filtering can also include substituting audio information of the device communication with predefined audio information, such as substituting at least one of a human voice or functional sound detected by the device with a different human voice or functional sound.

Filtering may also include removing information from the device communication, such as suppressing background sound information of the device communication, suppressing background image information of the device communication, removing a person's voice information from the

device communication, removing an object from the background information of the device communication, and removing the image background from the device communication.

BRIEF DESCRIPTION OF THE DRAWINGS

The headings provided herein are for convenience only and do not necessarily affect the scope or meaning of the 10 claimed invention.

In the drawings, the same reference numbers and acronyms identify elements or acts with the same or similar functionality for ease of understanding and convenience. To 15 easily identify the discussion of any particular element or act, the most significant digit or digits in a reference number refer to the figure number in which that element is first introduced.

FIG. 1 is a block diagram of an embodiment of a device communication arrangement.

20 FIG. 2 is a block diagram of an embodiment of an arrangement to produce filtered device communications.

FIG. 3 is a block diagram of another embodiment of a device communication arrangement.

25 FIG. 4 is a flow chart of an embodiment of a method of filtering device communications according to a cue.

FIG. 5 is a flow chart of an embodiment of a method of 30 filtering device communications according to a cue and a remote environment.

DETAILED DESCRIPTION

The invention will now be described with respect to various embodiments. The following description provides specific details for a thorough understanding of, and 35 enabling description for, these embodiments of the invention. However, one skilled in the art will understand that the invention may be practiced without these details. In other instances, well known structures and functions have not been shown or described in detail to avoid unnecessarily obscuring the description of the embodiments of the invention. References to "one embodiment" or "an embodiment" do not necessarily refer to the same embodiment, although 40 they may.

FIG. 1 is a block diagram of an embodiment of a device communication arrangement. A wireless device 102 comprises logic 118, a video/image sensor 104, an audio sensor 106, and a tactile/motion sensor 105. A video/image sensor (such as 104) comprises a transducer that converts light signals (e.g. a form of electromagnetic radiation) to electrical, optical, or other signals suitable for manipulation by logic. Once converted, these signals may be known as images or a video stream. An audio sensor (such as 106) comprises a transducer that converts sound waves (e.g. 45 audio signals in their original form) to electrical, optical, or other signals suitable for manipulation by logic. Once converted, these signals may be known as an audio stream. A tactile/motion sensor (such as 105) comprises a transducer that converts contact events with the sensor, and/or motion of the sensor, to electrical, optical, or other signals suitable for manipulation by logic. Logic (such as 116, 118, and 120) 50 comprises information represented in device memory that may be applied to affect the operation of a device. Software and firmware are examples of logic. Logic may also be embodied in circuits, and/or combinations of software and 55 circuits.

The wireless device 102 communicates with a network 108, which comprises logic 120. As used herein, a network

(such as 108) is comprised of a collection of devices that facilitate communication between other devices. The devices that communicate via a network may be referred to as network clients. A receiver 110 comprises a video/image display 112, a speaker 114, and logic 116. A speaker (such as 114) comprises a transducer that converts signals from a device (typically optical and/or electrical signals) to sound waves. A video/image display (such as 112) comprises a device to display information in the form of light signals. Examples are monitors, flat panels, liquid crystal devices, light emitting diodes, and televisions. The receiver 110 communicates with the network 108. Using the network 108, the wireless device 102 and the receiver 110 may communicate.

The device 102 or the network 108 identify a cue, either by using their logic or by receiving a cue identification from the device 102 user. Device 102 communication is filtered, either by the device 102 or the network 108, according to the cue. Cues can comprise conditions that occur in the local environment of the device 102, such as body movements, for example a facial expression or a hand gesture. Many more conditions or occurrences in the local environment can potentially be cues. Examples include opening or closing the device (e.g. opening or closing a phone), the deforming of a flexible surface of the device 102, altering of the device 102 orientation with respect to one or more objects of the environment, or sweeping a sensor of the device 102 across at least one object of the environment. The device 102, or user, or network 108 may identify a cue in the remote environment. The device 102 and/or network 108 may filter the device communication according to the cue and the remote environment. The local environment comprises those people, things, sounds, and other phenomenon that affect the sensors of the device 102. In the context of this figure, the remote environment comprises those people, things, sounds, and other signals, conditions or items that affect the sensors of or are otherwise important in the context of the receiver 110.

The device 102 or network 108 may monitor an audio stream, which forms at least part of the communication of the device 102, for at least one pattern (the cue). A pattern is a particular configuration of information to which other information, in this case the audio stream, may be compared. When the at least one pattern is detected in the audio stream, the device 102 communication is filtered in a manner associated with the pattern. Detecting a pattern can include detecting a specific sound. Detecting the pattern can include detecting at least one characteristic of an audio stream, for example, detecting whether the audio stream is subject to copyright protection.

The device 102 or network 108 may monitor a video stream, which forms at least part of a communication of the device 102, for at least one pattern (the cue). When the at least one pattern is detected in the video stream, the device 102 communication is filtered in a manner associated with the pattern. Detecting the pattern can include detecting a specific image. Detecting the pattern can include detecting at least one characteristic of the video stream, for example, detecting whether the video stream is subject to copyright protection.

FIG. 2 is a block diagram of an embodiment of an arrangement to produce filtered device communications. Cue definitions 202 comprise hand gestures, head movements, and facial expressions. In the context of this figure, the remote environment information 204 comprise a supervisor, spouse, and associates. The filter rules 206 define operations to apply to the device communications and the

conditions under which those operations are to be applied. The filter rules 206 in conjunction with at least one of the cue definitions 202 are applied to the local environment information to produce filtered device communications. Optionally, a remote environment definition 204 may be applied to the filter rules 206, to determine at least in part the filter rules 206 applied to the local environment information.

Filtering can include modifying the device communication to incorporate a visual or audio effect. Examples of 10 visual effects include blurring, de-saturating, color modification of, or snowing of one or more images communicated from the device. Examples of audio effects include altering the tone of, altering the pitch of, altering the volume of, adding echo to, or adding reverb to audio information 15 communicated from the device.

Filtering can include removing (e.g. suppressing) or substituting (e.g. replacing) information from the device communication. Examples of information that may suppressed as a result of filtering include the background sounds, the 20 background image, a background video, a person's voice, and the image and/or sounds associated with an object within the image or video background. Examples of information that may be replaced as a result of filtering include background sound information which is replaced with 25 potentially different sound information and background video information which is replaced with potentially different video information. Multiple filtering operations may occur; for example, background audio and video may both be suppressed by filtering. Filtering can also result in application of one or more effects and removal of part of the 30 communication information and substitution of part of the communication information.

FIG. 3 is a block diagram of another embodiment of a device communication arrangement. The substitution objects 304 comprise office, bus, and office sounds. The substitution objects 304 are applied to the substitution rules 308 along with the cue definitions 202 and, optionally, the 35 remote environment information 204. Accordingly, the substitution rules 308 produce a substitution determination for the device communication. The substitution determination 40 may result in filtering.

Filtering can include substituting image information of the device communication with predefined image information. An example of image information substitution is the 45 substituting a background of a present location with a background of a different location, e.g. substituting the office background for the local environment background when the local environment is a bar.

Filtering can include substituting audio information of the 50 device communication with predefined audio information. An example of audio information substitution is the substituting at least one of a human voice or functional sound detected by the device with a different human voice or functional sound, e.g. the substitution of bar background 55 noise (the local environment background noise) with tasteful classical music.

FIG. 4 is a flow chart of an embodiment of a method of filtering device communications according to a cue. At 402 it is determined that there is a cue. If at 404 it is determined 60 that no filter is associated with the cue, the process concludes. If at 404 it is determined that a filter is associated with the cue, the filter is applied to device communication at 408. At 410 the process concludes.

FIG. 5 is a flow chart of an embodiment of a method of 65 filtering device communications according to a cue and a remote environment. At 502 it is determined that there is a cue. At 504 at least one aspect of the remote environment is

determined. If at 506 it is determined that no filter is associated with the cue and with at least one remote environment aspect, the process concludes. If at 506 it is determined that a filter is associated with the cue and with at least one remote environment aspect, the filter is applied to device communication at 508. At 510 the process concludes.

Unless the context clearly requires otherwise, throughout the description and the claims, the words "comprise," "comprising," and the like are to be construed in an inclusive sense as opposed to an exclusive or exhaustive sense; that is to say, in the sense of "including, but not limited to." Words using the singular or plural number also include the plural or singular number respectively. Additionally, the words "herein," "above," "below" and words of similar import, when used in this application, shall refer to this application as a whole and not to any particular portions of this application. When the claims use the word "or" in reference to a list of two or more items, that word covers all of the following interpretations of the word: any of the items in the list, all of the items in the list and any combination of the items in the list.

What is claimed is:

1. A system comprising:

at least one communication device including at least:

circuity configured for engaging at least one synchronous communication between the at least one communication device and at least one receiving device in a remote environment;

one or more sensors including one or more of at least one audio sensor configured for sensing at least one of an audio signal stream or at least one video sensor configured for sensing at least one visual signal stream in a local environment for transmission to the at least one receiving device in the remote environment;

circuity configured for obtaining remote environment information including at least one identifier of at least one participant in the at least one synchronous communication in the remote environment;

circuity configured for detecting at least one manipulation of the at least one communication device by at least one user of the at least one communication device, wherein the at least one manipulation includes at least one of opening of the at least one communication device, closing of the at least one communication device, deforming a flexible surface of the at least one communication device, or altering an orientation of the at least one communication device;

circuity configured for determining one or more filter rules based at least partly on the detected at least one manipulation of the at least one communication device by the at least one user of the at least one communication device and the at least one identifier of at least one participant in the at least one synchronous communication in the remote environment;

circuity configured for filtering at least part of the at least one of an audio signal stream or a visual signal stream according to the one or more filter rules; and

circuity configured for transmitting the filtered at least one of the audio signal stream or the visual signal stream to the at least one receiving device.

2. The system of claim 1, wherein the circuitry configured for filtering at least part of the at least one of an audio signal stream or a visual signal stream according to the one or more filter rules comprises:

circuity configured for replacing at least some content of the at least one of an audio signal stream or a visual signal stream according to the one or more filter rules.

3. The system of claim 1, wherein the circuitry configured for filtering at least part of the at least one of an audio signal stream or a visual signal stream according to the one or more filter rules comprises:

circuity configured for removing at least one voice of the at least one audio signal stream according to the one or more filter rules.

4. The system of claim 1, wherein the circuitry configured for filtering at least part of the at least one of an audio signal stream or a visual signal stream according to the one or more filter rules comprises:

circuity configured for removing at least some video content of the at least one visual signal stream according to the one or more filter rules.

5. The system of claim 1, wherein the circuitry configured for filtering at least part of the at least one of an audio signal stream or a visual signal stream according to the one or more filter rules comprises:

circuity configured for replacing at least some video content of the at least one visual signal stream according to the one or more filter rules.

6. The system of claim 1, wherein the circuitry configured for filtering at least part of the at least one of an audio signal stream or a visual signal stream according to the one or more filter rules comprises:

circuity configured for substituting at least one voice of the at least one communication with at least one different voice in the at least one audio signal stream according to the one or more filter rules.

7. The system of claim 1, wherein the circuitry configured for filtering at least part of the at least one of an audio signal stream or a visual signal stream according to the one or more filter rules comprises:

circuity configured for removing at least one background sound of the at least one audio signal stream according to the one or more filter rules.

8. The system of claim 1, wherein the circuitry configured for filtering at least part of the at least one of an audio signal stream or a visual signal stream according to the one or more filter rules comprises:

circuity configured for replacing at least one background sound of the at least one communication with at least one different background sound according to the one or more filter rules.

9. The system of claim 1, wherein the circuitry configured for filtering at least part of the at least one of an audio signal stream or a visual signal stream according to the one or more filter rules comprises:

circuity configured for replacing at least one background sound of the at least one communication with at least one audio effect according to the one or more filter rules.

10. The system of claim 1, wherein the circuitry configured for filtering at least part of the at least one of an audio signal stream or a visual signal stream according to the one or more filter rules comprises:

circuity configured for replacing at least one background noise of the at least one communication with at least some music according to the one or more filter rules.

11. The system of claim 1, wherein the circuitry configured for filtering at least part of the at least one of an audio signal stream or a visual signal stream according to the one or more filter rules comprises:

circuitry configured for altering at least one of tone, pitch, or volume of the at least one communication according to the one or more filter rules.

12. The system of claim 1, wherein the circuitry configured for filtering at least part of the at least one of an audio signal stream or a visual signal stream according to the one or more filter rules comprises:

circuitry configured for filtering at least part of the at least one communication including adding one or more audio effects according to the one or more filter rules.

13. The system of claim 1, wherein the circuitry configured for filtering at least part of the at least one of an audio signal stream or a visual signal stream according to the one or more filter rules comprises:

circuitry configured for suppressing at least part of the at least one communication according to the one or more filter rules.

14. The system of claim 1, wherein the circuitry configured for filtering at least part of the at least one of an audio signal stream or a visual signal stream according to the one or more filter rules comprises:

circuitry configured for filtering at least part of the at least one phone communication according to the one or more filter rules.

15. The system of claim 1, wherein the circuitry configured for filtering at least part of the at least one of an audio signal stream or a visual signal stream according to the one or more filter rules comprises:

circuitry configured for filtering at least part of the at least one audiovisual communication according to the one or more filter rules.

16. The system of claim 1, wherein the circuitry configured for obtaining remote environment information including at least one identifier of at least one participant in the at least one synchronous communication in the remote environment includes:

at least one of:

circuitry configured for receiving a cue identification from the at least one communication device;

circuitry configured for identifying participants in the at least one communication present in the remote environment;

circuitry configured for detecting one or more signals in a context of the at least one receiving device;

circuitry configured for detecting one or more sounds in the remote environment;

circuitry configured for detecting at least one specific sound in the remote environment;

circuitry configured for detecting at least one pattern of an audio stream from the remote environment;

circuitry configured for detecting at least one specific image in the remote environment;

circuitry configured for detecting at least one pattern of a video stream from the remote environment;

circuitry configured for detecting one or more conditions in the context of the at least one receiving device; or

at least one video sensor configured to detect at least one of hand gestures, head movements, facial expressions, body movements, or sweeping a sensor of the device across at least one object of an environment.

17. The system of claim 1, wherein the at least one communication device includes:

at least one of a cell phone, a wireless device, or a computer.

18. The system of claim 1, wherein the circuitry configured for detecting at least one manipulation of the at least one communication device by at least one user of the at least one communication device comprises:

at least one of:

circuitry configured for detecting at least one manipulation of the at least one communication device by at least one user of the at least one communication device including at least one body movement of the at least one user of the at least one communication device;

circuitry configured for detecting at least one manipulation of the at least one communication device by at least one user of the at least one communication device including at least one hand gesture of the at least one user of the at least one communication device;

circuitry configured for detecting at least one manipulation of the at least one communication device by at least one user of the at least one communication device including at least one facial expression of the at least one user of the at least one communication device; or

circuitry configured for detecting at least one manipulation of the at least one communication device by at least one user of the at least one communication device including at least one head movement of the at least one user of the at least one communication device.

19. The system of claim 1 wherein the at least one receiving device includes

at least one of a cell phone, a wireless device, a computer, a video/image display, or a speaker.

20. A method at least partly performed using one or more processing components in at least one communication device, the method comprising:

engaging at least one synchronous communication between at least one communication device and at least one receiving device in a remote environment;

sensing at least one of an audio signal stream via at least one communication device audio sensor or a visual signal stream via at least one communication device video sensor in a local environment for transmission to the at least one receiving device in the remote environment;

obtaining remote environment information including at least one identifier of at least one participant in the at least one synchronous communication in the remote environment;

detecting at least one manipulation of the at least one communication device by at least one user of the at least one communication device, wherein the at least one manipulation includes at least one of opening of the at least one communication device, closing of the at least one communication device, deforming a flexible surface of the at least one communication device, or altering an orientation of the at least one communication device;

determining one or more filter rules based at least partly on the detected at least one manipulation of the at least one communication device by the at least one user of the at least one communication device and the at least one identifier of at least one participant in the at least one synchronous communication in the remote environment;

filtering at least part of the at least one of an audio signal stream or a visual signal stream according to the one or more filter rules; and

transmitting the filtered at least one of an audio signal stream or a visual signal stream to the at least one 5 receiving device.
